(57) **CLAIM**

The ornamental design for an automated assay system, as shown and described.

DESCRIPTION

FIG. 1 is a front view of the automated assay system showing a first embodiment of our new and ornamental design;

FIG. 2 is a perspective view of the first embodiment; FIG. 3 is an alternate perspective view of the first embodiment;

FIG. 4 is a front view of the automated assay system showing a second embodiment of our new and ornamental design;

FIG. 5 is a perspective view of the second embodiment; and, FIG. 6 is an alternate perspective view of the second embodiment.

The broken lines are included for the purpose of illustrating portions of the article that form no part of the claimed design.
